VALVE GRINDER

Arthur H. Anderson, Lakeville, Minn.

Application April 20, 1950, Serial No. 157,101

4 Claims. (Cl. 51—48)

1

The herein disclosed invention relates to valve grinders and has for an object to provide a valve grinder by means of which a valve such as used with automobile engines may be ground to form a surface absolutely concentric with the axis of the valve stem.

Another object of the invention resides in providing a valve grinder in which the valve is supported for rotation by means of bearings directly engaging the valve stem of the valve.

A still further object of the invention resides in constructing the bearings as blocks having V-shaped notches in which the valve stem is rotatable and in further utilizing an arm engaging the valve stem and spring biased to urge the stem into said bearings.

An object of the invention resides in providing a power driven grinding wheel guided for movement past the surface to be ground and in further providing an adjustable end stop for engagement with the end of the valve stem to limit the depth of the grinding.

A still further object of the invention resides in forming said stop as a screw adjustable by rotation to limit the movement of the valve stem along its bearings.

Another object of the invention resides in providing a driven shaft substantially coaxially disposed with reference to the axis of the valve stem and situated opposite the valve head and in forming said shaft with a longitudinally extending hole, made square at one end, and in further providing a spindle slidable along said hole and having a square portion fitting the square portion of said hole and being driven thereby.

Another object of the invention resides in providing a driving member at the end of said spindle, preferably of a flexible material such as rubber or the like, and frictionally engaging the valve head to rotate the valve and in further providing in said hole a compression coil spring engaging said spindle and urging said driving member against said valve head.

The structure shown in the drawings consists of a base on which is mounted a support for a valve. This support comprises two bearings having V-shaped notches therein for the reception of the valve stem. A swinging arm spring biased into engagement with the valve stem holds the valve stem rotatable in said V-shaped notches. An adjustable end stop engages the end of the valve stem and holds the valve in adjusted position. The valve is rotated by means of a spindle slidably mounted in a longitudinal extending hole in a driven shaft. This shaft is in substantial

2

alignment with the valve stem and a square portion on the spindle and engaging a square end of said shaft drives the spindle. The spindle is provided with a cup-shaped friction member preferably constructed of rubber or other resilient material which engages the valve head and procures rotation thereof. A spring in the hole in the shaft engages the spindle and urges the driving member into engagement with the valve stem. The shaft is rotated by means of a motor and suitable reduction gearing. For grinding the valve a grinding wheel is employed which is driven by a motor. The said wheel and motor are mounted as a unit for sliding movement so that the surface of the grinding wheel passes the contact surface of the valve and grinds the same.

In the drawings:

Fig. 1 is a plan view of a valve grinder illustrating an embodiment of the invention.

Fig. 2 is an elevational sectional view taken on line 2—2 of Fig. 1 and drawn to a greater scale.

Fig. 3 is a longitudinal elevational sectional view taken on line 3—3 of Fig. 1 and drawn to a greater scale.

Fig. 4 is a cross sectional view taken on line 4—4 of Fig. 1 and drawn to a greater scale.

The invention comprises a base 10 constructed of a plate of metal which is cut to form an elongated portion 11 with an angular portion 12 extending outwardly therefrom. On the elongated portion 11 is disposed a support 13 which consists of a channel member 40 which has a web 41 and flanges 42 projecting upwardly therefrom. The ends of the flanges at the left of said support are cut away as shown in Fig. 1, while the web 41 extends throughout the length of the support. The said support further comprises two angle members 14 and 15. These angle members have depending flanges 16 and coplanar flanges 17. The flanges 16 are welded to the web 41 of channel member 40 by welds 18 and are so arranged that the edges of the flanges 17 form a groove 19 therebetween. Secured to one end of the web 41 of channel member 40 and to the ends of the angle members 14 and 15 is another angle member 95 which has flanges 96 and 97. The flange 96 overlies the web 41 while the flange 97 buts up against the ends of the flanges 16 of the angle members 14 and 15. All of these parts are welded together to stiffen and reinforce the support 13 and to maintain the spacing of the flanges 17 of angle members 14 and 15 forming the slot 19. The support 13 is pivotally attached

to the base 10 by means of a cap screw 98. This cap screw extends through the web 41 of channel member 40 intermediate the ends thereof and is screwed into said base. In addition another cap screw 99 is employed which extends through an arcuate slot 100 formed in the flange 96 of angle member 95 and in the web 41 of channel member 40 and which is similarly screwed into base 10. This construction gives a limited angular adjustment of the entire support 13 for a purpose which subsequently will become readily apparent. Additional tapped holes may also be formed in the base 10 to permit of further adjustment of the angularity of the support 13 with reference to the base 10.

Mounted on the flanges 17 of angle members 14 and 15 are two bearings 20 and 21 which are formed with V-shaped notches 22. These bearings have threaded shanks 23 which extend through the groove 19 and which have screwed on them nuts 24. By means of this construction the bearings 20 and 21 may be disposed along the support 13 at any locality therealong. The bearings 20 and 21 rotatably support a valve such as is indicated at 25. This valve has a valve stem 26 and a valve head 27 formed with a beveled contact surface 28. The valve is rotatably mounted in the bearings 20 and 21 by placing the valve stem 26 in the V-shaped notches 22 in the bearings 20 and 21.

For holding the valve stem 26 in the bearings 20 and 21 a swinging lever 29 is employed which is constructed from sheet metal bent U-shaped in form to provide a plate-like portion 30 with flanges 31 depending therefrom. A pintle 32 passes through the flanges 31 of lever 29 and through posts 33 welded to the flange 17 of angle member 15. The forward portions of the flanges 31 are adapted to engage the stem 26 and when the lever is swung in a counter clockwise direction as viewed in Fig. 4 the valve stem is urged into the notches 22. A leaf spring 34 secured to the flange 16 of angle member 15 by means of screws 35 has a movable end 36 which engages the rearward edge of the plate-like portion 30 of lever 29 and urges the same upwardly. This urges the forward portions of the flanges 31 downwardly and against the valve stem 26 to hold the same journaled in the bearings 20 and 21.

To limit longitudinal movement of the valve stem 26 along the bearings 20 and 21 an end stop 37 is employed. This stop consists of a screw which is screwed into two threaded posts 38 which are attached to the support 13. These posts have parts 101 which extend through the slot 19 and which are secured to a bar 102 disposed below the flanges 17 of the angle members 14 and 15. A cap screw 103 extends through the slot 19 and is screwed into said bar. By means of this construction the end stop 37 may be further adjusted relative to the support 13. The inner end of the screw 37 engages the end of the valve stem 26 and restrains longitudinal movement of the valve stem in a direction toward the left as viewed in Fig. 1. A crank 39 or other turning device secured to the end of the screw 37 serves to rotate the same and procure accurate adjustment of the valve.

Mounted on the support 13 are two cross bars 44 which have bearings 43 secured to the same. These cross bars overlie the upper edges of the flanges 42 of channel member 40 and are welded thereto. The bearings 43 have bores 45 which are in alignment with one another and substan-

tially in alignment with the axis of the valve stem 26. Rotatably mounted in these bearings is a shaft 46. This shaft has a longitudinally extending hole 47 in the same which is disposed in coaxial alignment with reference to the axis of said shaft. The forward portion of said hole is square as indicated at 48 while the rearward portion of said hole is constructed as a bore 49 of a diameter slightly greater than the diagonal dimension of the portion 48 of the said hole. In the hole 47 is slidably mounted a spindle 149 which is square and which engages the square portion 48 of said hole and is driven thereby. This spindle has formed on the end of it a knurled head 50 to which a driving member 51 is attached. This driving member is preferably constructed of resilient material such as rubber or the like and has a boss 52 apertured to receive the head 50 and secured thereto. The said driving head has a cup-shaped portion 53 formed with a contact surface 54 adapted to engage the face 55 of the valve head 27. A compression coil spring 56 is received within the bore 49 and is seated at one end against the said spindle 149. The other end of said spring is seated against a cotter pin 57 extending through the end of the shaft 46. Mounted on the shaft 46 between the bearings 43 is a sheave 58 which has a boss 59 on the same. The said boss is of a width such as to fit between the two bearings 43 and prevents endwise movement of the shaft 46. By means of this construction the driving member 51 is urged against the valve head 27 and the stem 26 against the end stop 37. The boss 59 receives the reaction from the spring 56 against the cotter pin 57.

The sheave 58 may be driven by means of an electric motor 60 mounted on the channel member 40 above the bearings 43. This motor has a reduction transmission which is enclosed within a housing 61 in the end of the said motor. This transmission includes a driven shaft 62 on which is mounted a sheave 63. A belt 64 passes over the sheave 63 and the sheave 58 and serves to drive the shaft 46 at a reduced rate of speed.

For grinding the surface 28 of the valve 25 a grinding unit 93 is employed. This grinding unit includes a grinding wheel 65 which is mounted on an arbor 66. This arbor is journaled in an elongated bearing 67 which is supported in the following manner: For the purpose a support 68 is employed which has two upright legs 69 and 70 and a web 71 connected thereto. The bearing 67 is bolted by means of bolts 72 to the web 71. At the upper ends of the legs 69 and 70 are formed flanges 73 and 74 which lie in a common plane. These flanges support an electric motor 75. This motor has a base 76 and through which four bolts 77 extend. These bolts have their heads 78 welded to the flanges 73 and 74 and nuts 79 and 80 on said bolts engage the base 76 and hold the motor properly supported. The arbor 66 has a sheave 81 mounted thereon while the armature shaft 82 of the motor 75 has a sheave 83 mounted thereon. A belt 84 passes over these sheaves and drives the arbor 66.

The unit 93 which comprises the motor 75 and the arbor 66 together with the wheel 65 and bearings 67 and support 68 are mounted for sliding movement along the angular portion 12 of base 10. This is accomplished by means of two angle guides 85 which lie along the legs 69 and 70 and are bolted to the portion 12 of base 10 by means of cap screws 86 extending through said guides and screwed into the base 10. These guides are sufficiently free from the support 68 to permit of

freely sliding the unit along the same. Movement of the unit is procured by means of a lever 87. This lever is pivoted by means of a bolt 88 to a bracket 89 secured to the guide 85 by welding or otherwise. This lever has a slot 90 in the same through which a pin 91 extends. The pin 91 is secured to the flange 73 of the support 68. It will readily be comprehended that swinging of the lever 87 will cause the entire unit 93 to move along the guides 85 and cause the surface 92 of the wheel 65 to pass and grind the surface 28 of the valve head 27 of valve 25.

In operation the two bearings 20 and 21 are properly adjusted to support the valve stem 26 with the valve head 27 in proper position to be ground by the wheel 65. The valve 25 is then mounted and the lever 29 brought to bear against the valve stem 26. In mounting the valve 25 in the bearings 20 and 21 the driving member 51 is moved toward the right as viewed in Figs. 1 and 3 to bring the same out of contact with the valve. Upon release of the said driving member, the spring 56 causes the said driving member to contact the face 55 of the valve head 27 and to force the end of the valve stem 26 into engagement with the stop 37. The angularity of the support 13 is next adjusted by loosening cap screws 93 and 99 and by shifting the said support bodily about the bolt 98 as a pivot until the surface 28 of valve 25 is parallel with the guides 85. Bolts 98 and 99 are then tightened. The motor 69 is next energized and also the motor 75. The unit 93 is then slid along the guides 85 by means of lever 87 and the position of the valve surface 28 adjusted by rotating screw 37 through the crank 39. As the valve is driven by the driving member 51 the same rotates accurately in the bearings 20 and 21 and the surface 28 is ground concentric with the axis of the said valve stem and at the proper angle. The V-notches 22 in the bearings 20 and 21 accommodate valve stems of slightly different diameters and the driving member 51 will also drive a valve which is slightly out of alignment with the axis of the shaft 46. However, when valves having valve stems of greater variation are to be ground other bearings similar to the bearings 20 and 21 may be employed and mounted in the groove 19. Likewise other driving members 51 of different sizes may be placed on the head 59 to correspond with different valve heads.

The advantages of the invention are apparent. The valve is ground absolutely concentric with the axis of the valve stem. This causes the valve to fit perfectly on the valve seat. With this invention the desired results are not dependent upon the accuracy of a chuck. The device can be constructed at less expense than similar valve grinders using chucks. The valve stem is rapidly mounted for rotation. The device can be adjusted to take various lengths of valve stems as well as valves and valve stems of different diameters. Also the angularity of the ground surface may be adjusted. Adjustment and operation of the device is extremely simple.

Changes in the specific form of the invention, as herein described, may be made within the scope of what is claimed without departing from the spirit of the invention.

Having described the invention, what is claimed as new and desired to be protected by Letters Patent is:

1. In a grinder for a valve having a stem and a head, a support, spaced bearings carried by said support and having aligning V-shaped

notches therein for receiving and supporting the stem of the valve for rotary and axial movement, an arm, guide means between said arm and support and guiding said arm for movement into and out of engagement with the valve stem, resilient means reacting against a part fixed relative to the support and engaging said arm for urging said arm toward said stem and said stem into said notches, said stem being slidable relative to said arm, a grinding wheel rotatably supported with reference to said support, guide means carried by said support and guiding said grinding wheel for movement to cause the grinding surface of the wheel to pass the valve head contact surface and grind the same, an adjustable non-yieldable end stop carried by the support and engageable with the free end of the valve stem to limit axial movement of the valve in a direction toward the free end of the valve stem, rotary driving means carried by the support and engageable with said valve head to rotate the same, guide means on the support engaging and guiding said drive means for axial movement and resilient means acting between said guide means and drive means for urging said drive means toward said valve and the valve stem against said end stop.

2. In a grinder for a valve having a stem and a head, a support, spaced bearings carried by said support and having aligning V-shaped notches therein for receiving and supporting the stem of the valve for rotary and axial movement, an arm, guide means between said arm and support and guiding said arm for movement into and out of engagement with the valve stem, resilient means reacting against a part fixed relative to the support and engaging said arm for urging said arm toward said stem and said stem into said notches, said stem being slidable relative to said arm, a grinding wheel rotatably supported with reference to said support, guide means carried by said support and guiding said grinding wheel for movement to cause the grinding surface of the wheel to pass the valve head contact surface and grind the same, an adjustable non-yieldable end stop carried by the support and engageable with the free end of the valve stem to limit axial movement of the valve in a direction toward the free end of the valve stem, rotary driving means carried by the support and including a spindle revoluble about its axis, a driving member carried by the end of the spindle for frictionally engaging the end of the valve head, said valve head being slidable relative to said driving member in a direction transverse to the axis of said spindle and resilient means acting on said spindle for urging said driving member against said valve head and the valve stem against said end stop.

3. In a grinder for a valve having a stem and a head, a support, spaced bearings carried by said support and having aligning V-shaped notches therein for receiving and supporting the stem of the valve for rotary and axial movement, an arm, guide means between said arm and support and guiding said arm for movement into and out of engagement with the valve stem, resilient means reacting against a part fixed relative to the support and engaging said arm for urging said arm toward said stem and said stem into said notches, said stem being slidable relative to said arm, a grinding wheel rotatably supported with reference to said support, guide means carried by said support and guiding said

grinding wheel for movement to cause the grinding surface of the wheel to pass the valve head contact surface and grind the same, an adjustable non-yieldable end stop carried by the support and engageable with the free end of the valve stem to limit axial movement of the valve in a direction toward the free end of the valve stem, a shaft disposed substantially coaxially with reference to said valve stem, bearings therefor carried by said support, said shaft having a central longitudinal hole therein, a spindle disposed within said hole and slidable axially with respect to said shaft, a resilient cup carried by said spindle and having a surface for engaging the valve head, means acting between said shaft and spindle and restraining relative rotational movement therebetween and resilient means within said hole and engaging said spindle for urging said cup against said valve head.

4. In a grinder for a valve having a stem and a head, a support, spaced bearings carried by said support and having aligning V-shaped notches therein for receiving and supporting the stem of the valve for rotary and axial movement, an arm, guide means between said arm and support and guiding said arm for movement into and out of engagement with the valve stem, resilient means reacting against a part fixed relative to the support and engaging said arm for urging said arm toward said stem and said stem into said notches, said stem being slidable relative to said arm, a grinding wheel rotatably supported with reference to said support, guide means carried by said support and guiding said
